US0D1068746S

(12) **United States Design Patent** (10) **Patent No.:** **US D1,068,746 S**
(45) **Date of Patent:** **** Apr. 1, 2025**

(54) **SECURITY DEVICE**

(71) Applicant: **Sensormatic Electronics, LLC**, Boca Raton, FL (US)

(72) Inventors: **Channing E. Miller**, Fort Lauderdale, FL (US); **Kelvin L. Hunter**, Lake Worth, FL (US); **Sergio M. Perez**, Lake Worth, FL (US)

(73) Assignee: **Sensormatic Electronics, LLC**, Boca Raton, FL (US)

(**) Term: **15 Years**

(21) Appl. No.: **29/875,228**

(22) Filed: **May 1, 2023**

(51) LOC (15) Cl. **14-03**

(52) U.S. Cl.

USPC **D14/238**; D13/184

(58) **Field of Classification Search**

USPC D14/137, 138, 148, 155, 167, 168, D14/230-238, 240, 242, 265, 299, 343, D14/358; D13/184

CPC H01Q 13/10; H01Q 13/38; H01Q 13/36

(57) **CLAIM**

The ornamental design for the security device as shown and described.

DESCRIPTION

FIG. 1 is a front-right perspective view of a security device showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and

FIG. 7 is a bottom view of the design shown in FIG. 1; and,

FIG. 8 is a magnified view of the highlighted section shown in FIG. 2.

The broken lines shown in the figures are included for the purposes of illustrating portions of the security device and form no part of the claimed design.

1 Claim, 6 Drawing Sheets
